United States Patent Office.

JOHN W. HOLLINGSWORTH, OF MOUNT VERNON, INDIANA.

Letters Patent No. 101,877, dated April 12, 1870.

IMPROVEMENT IN MOLDS FOR METALS.

The Schedule referred to in these Letters Patent and making part of the same

To all whom it may concern:

Be it known that I, JOHN W. HOLLINGSWORTH, of Mt. Vernon, in the county of Posey and State of Indiana, have invented certain new and useful Improvements in Molds for Metals; and I do hereby declare that the following is a full, clear, and exact description thereof, reference being had to the accompanying drawings and to the letters of reference marked thereon which form a part of this specification.

The nature of my invention consists in the construction of a device by means of which molten metal may be forced into a mold.

In order to enable others skilled in the art to which my invention appertains to make and use the same, I will now proceed to describe its construction and operation, referring to the annexed drawings, in which—

Figure 1 is a perspective view, and

Figure 2, a longitudinal vertical section of my device.

A represents the flask in which the mold is formed of plaster and sand, or other suitable material.

B is a cylinder opening into the flask A, and into which the fused metal is poured by way of the funnel C.

D is the handle to which the flask and cylinder are attached.

In the cylinder B is a plunger, E, operated by means of a rod, G.

The operation is as follows:

The mold is formed in the flask, with a gate opening from the mold to the inner mouth of the cylin-

der B; the plunger E is now thrust in, and the machine placed in the fire until the flask, mold, and cylinder all assume a red heat.

The plunger is now withdrawn to the outer end of the cylinder, and the melted metal poured into the cylinder at the funnel C. The plunger is now brought back or thrust in upon the melted metal within the cylinder, until the metal is forced through the gate into the mold, and every interstice of the mold is filled.

The small perforations or holes *i i* around the upper margin of the upper half of the flask A are for the introduction of small wires, during the formation of the upper half of the mold. When the mold is finished these wires are withdrawn, leaving vent-holes for the escape of air and surplus metal during the operation of pressing or plunging the metal into the mold.

Having thus fully described my invention,

What I claim as new, and desire to secure by Letters Patent, is—

1. The metal mold, constructed as described, and so arranged as to force the metal into the mold by mechanical means, substantially as set forth.

2. The flask A, cylinder B, funnel C, handle D, and plunger E, all constructed, combined, and arranged substantially as and for the purposes herein set forth.

In testimony that I claim the foregoing as my own, I affix my signature in presence of two witnesses.

JOHN W. HOLLINGSWORTH.
